attorney.

UNITED STATES PATENT OFFICE

ROBERT W. CRAIG, OF BURBANK, CALIFORNIA, ASSIGNOR TO THE NATIONAL SUPPLY COMPANY, OF TOLEDO, OHIO, A CORPORATION OF OHIO

DRILL STEM FOR FLUSH JOINT DRILLING APPARATUS

Application filed October 8, 1929. Serial No. 398,176.

My invention relates to well drilling apparatus and more particularly to a novel drill stem for use in connection with a rotary drilling apparatus having a stuffing box in the top of a casing head, in which stuffing box a flush-joint drill pipe and stem is run. In drilling oil wells under conditions where the rock pressures encountered must be held in check or under control in order to prevent the gas from flowing around the drill stem at the top of the well, drill pipes having joints flush with the outer surfaces of the drill pipe sections have been proposed, the drill pipe being reciprocable and rotatable with a fluid-tight fit in the stuffing boxes on the upper ends of the casing heads in which the drill pipes work. For drilling wells under the conditions specified I have designed a novel drill stem having its upper portion non-circular, preferably rectangular, to fit a correspondingly-shaped opening in the drive bushing in a rotary drilling machine and having its lower portion circular in cross-section and fitting in the stuffing box on the top of the casing head, the diameter of the lower portion being the same as that of the drill pipe and the joint members which connect the sections of the drill pipe in series.

Referring to the accompanying drawing, Fig. 1 shows a side elevation of my novel drilling stem in connection with a rotary table and a casing head and a drill pipe carried by the drill stem, some parts being omitted and other parts being broken off or shown in section. Fig. 1 shows a drill stem provided with the first short or pony joint section. Fig. 2 is an elevation of the drill pipe with both ends broken off and with two pony joints therein. Fig. 3 is like Fig. 2, but shows three pony joints in the drill stem. Fig. 4 is like Fig. 3, but with a full length drill pipe section substituted for the three pony joints shown in Fig. 3.

On the drawing 1 designates a rotary table driven by any suitable means, not shown. The table has the drive bushing 2 containing the slips 3 in which the rectangular upper section 4 of the drill stem 5 slidingly fits, the lower section 6 of the drill stem being

circular in cross-section and rotatable and reciprocable in the stuffing box 7 on the upper end of the casing head 8 on the upper end of the well casing, not shown. The lower end of the drill stem section 6 is secured by the pipe joint members 9 to the upper end of the drill pipe section or pony joint 10 whose lower end is secured by pipe joint members 11 to the upper end of a full length drill pipe section 12. The latter is secured by the pipe joint members 13 to the upper end of a second full length drill pipe section 14, to which other drill pipe sections, not shown, are connected in a manner well known. The sections 12 and 14 are each assumed to be about three times the length of the pony joint or the drill stem section 6.

I prefer to make my drill stem about 16 feet in length and to have each of the sections 4 and 6 about 8 feet long. Accordingly, during drilling operations the travel of the drill stem 5 is limited to the distance between the table 1 and the stuffing box 7 which distance is about equal to the length of the section 6 of the drill stem.

It is not necessary to use the drill stem 5 until the drilling of the well has proceeded to such a depth that it is necessary or advisable to provide for the control of the rock pressure. Until this depth is reached the stuffing box 7 is not used and the drilling proceeds in the usual manner wherein a standard drill stem about 32 feet long, for example, is employed, it being rectangular in cross-section from end to end. With a full length section of drill pipe connected below to the drill string and above to the lower end of the drill stem which is slidingly fitted in the table, the latter is rotated, the drill string being lowered as the drilling proceeds until the top of the drill stem reaches the table. The drill string is then raised until the top of the upper section of the drill string is above the table whereupon the drill string is suspended and the drill stem detached from the string and another section of drill pipe is attached thereto. The string is lowered with the drill stem attached to the top thereof. The table 1 is again rotated until the top of the drill stem reaches the table whereupon the

process described is repeated until it is deemed advisable to attach the stuffing box 7 to the casing head 8 and to substitute the drill stem 5 for the standard all-rectangular stem.

5 Assuming that the drill pipe section 12 was the last section added when drilling with the said standard drill stem and that the drilling stopped when the upper end of the section 12 was about 12 feet or twice the 10 length of the drill stem section 6 below the table 1, the drill string is raised to bring the upper end of the section 12 above the table. The drill string is then suspended, the standard drill stem is removed, the pony joint 10 is 15 connected to the upper end of the section 12, and my drill stem 5 is connected to the upper end of the pony joint 10. The drill string is then lowered until it rests on the bottom of the well hole when the parts will be as in 20 Fig. 1, whereupon the lower end of the rectangular drill stem section 4 is in the table 1, as shown in Fig. 1. The table is rotated causing the drill string to be rotated, the latter being lowered as the drilling proceeds.

25 When the upper end of the stem section 4 enters the table the table is stopped and the drill string is raised and another section or pony joint, as 15, is inserted between the stem 5 and the pony joint 10. The string is again lowered and the drilling again proceeds, with the parts as in Fig. 2, until the upper end of the stem section 4 again enters the table whereupon the string is raised and another pony joint, as 16, is inserted between the stem section 4 and the pony joint 15. The string is again lowered and the drilling again proceeds, with the parts as in Fig. 3, until the upper end of the stem section 4 again enters the table whereupon the string is raised until the section 12 is above the table. The string is then suspended and the three pony joints, 10, 15 and 16 are removed and full length drill pipe section 17 whose length is 35 about equal to the combined lengths of the said three pony joints, is attached to the section 12. Then the drilling proceeds as before, the pony joints 10, 15 and 16 being again inserted in the drill string as before described. The cycle of attaching the pony joints serially, then removing them and then attaching a full length joint or drill pipe section to the string is repeated as many times as may be required or desired.

50 55 I do not restrict my invention to the use of drill stems or the sections 4 and 6 thereof to any definite lengths nor to the number of pony joints to be used serially before substituting a regular full length drill stem 60 therefor.

To use full length joints in place of the short or pony joint would require the drill stem to be about 64 feet long in order to drill the usual 32 feet at each operation of the 65 table. Such a stem is clearly not desirable

and, besides, it would require the stuffing box to be located 32 feet down in a cellar or pit which would have to be several feet deeper to accommodate the casing head.

70 The length of the circular section 6 and of each of the pony joints should not be longer than the distance from the stuffing box up to the point above which the lower end of the section 4 will lose driving connection with the rotary table. The maximum distance drilled at one operation is equal to the distance the lower end of the section 4 travels from its highest driving connection with the table to the top of the stuffing box. The length of the longest pony joint to be inserted and used in the string equals the depth drilled at the last drilling operation. If the pony joint is longer than that depth the section 4 will lose driving connection with the rotary table when the string is lowered so that it stands on the bottom of the well hole. The pony joint should not exceed in length the depth of the last drilling operation whether or not the lower end of the section 4 descended during the operation the entire way to the stuffing box.

75 80 85 90 95 It is to be understood that the drill stem 5 and the pony joints need not be used in ordinary drilling operations when there are no indications that high pressure is to be encountered in the well. Up to such indications a drill stem non-circular in cross-section from end to end would be used with which there would be no circular portion working in a stuffing box on the top of the casing head. In such cases no stuffing box would be used. But when gas pressure in the well is anticipated then the stuffing box must be used and a round drill stem section is necessary. If a flush joint drill pipe is to be used with that drill stem, it would be necessary to use pony joints, the length of each not being greater than the depth the hole was drilled at the last drilling operation.

100 105 110 115 120 It is advisable to make the stem 5 of a single jointless piece. Due to rather crude field conditions it is generally impossible to provide and maintain an exact alignment of the center lines of the stuffing box and the rotary table with the result that the portion of the drill pipe or stem between the table and stuffing box is subject to fatigue stresses that eventually produce failures where the drill stem is made of two sections screwed together, for example, at the junction of the sections 4 and 6.

I claim:

125 130 135 In a rotary well drilling apparatus, a rotary table with a vertical non-circular opening, a casing head below the rotary table, a stuffing box on the casing head spaced below the table, a flush-joint circular drill pipe comprising a tandem series of relatively long lengths and embraced by the stuffing

box, and a plurality of materially shorter lengths of drill pipe, the length of each shorter length being about the distance between the table and the stuffing box and each having the same diameter as the drill pipe in combination with a vertically movable drill stem having an upper portion with a

cross-section corresponding to that of the said opening and having also a lower circular portion rigid therewith and having the same diameter as the drill pipe lengths, the lengths of the two sections of the drill stem being substantially the same.
